(57) **CLAIM**

The ornamental design for a set of electronic devices, as shown and described.

DESCRIPTION

FIG. 1 is a perspective view of an embodiment of our new design of a set of electronic devices;
FIG. 2 is a front view thereof;
FIG. 3 is a rear view thereof;
FIG. 4 is a first side view thereof;
FIG. 5 is a second side view thereof;
FIG. 6 is a top view thereof; and,
FIG. 7 is a bottom view thereof.

The oblique lines represent a transparent or translucent surface.

The cable is shown with a symbolic break in its length. The appearance of any portion of the article beyond the break lines forms no part of the claimed design.

The broken lines shown in the Figures are for the purposes of illustrating portions of the set of electronic devices which form no part of the claimed design.
